UNITED STATES PATENT OFFICE.

HARRY A. BARRETT, OF PHILADELPHIA, PENNSYLVANIA, ASSIGNOR TO BARRETT
LOCK COMPANY, INC., A CORPORATION OF DELAWARE.

PERMUTATION LOCK.

Application filed May 13, 1925, Serial No. 29,886. Renewed May 19, 1928.

This invention, generally stated, relates to permutation locks and has more especial relation to that type commonly referred to as keyless padlocks.

5 The leading object of the present invention is to provide a simple, efficient and comparatively inexpensive lock of the character stated in which springs are eliminated and the number of parts reduced to a minimum without 10 sacrificing essential elements necessary for security of the locking means. Other objects reside in the provision of general details of construction and in the arrangement, connection and combination of parts for attaining 15 the results sought by the leading object. Other and further objects not at this time appearing will be hereinafter more specifically referred to.

The invention consists of the novel construction hereinafter described and finally claimed.

The nature, characteristic features and scope of the invention will be more fully understood from the following description 25 taken in connection with the accompanying drawings forming part hereof, and in which:

Fig. 1, is a view in elevation of the lock.

Fig. 2, is a view similar to Fig. 1 with the front plate and its dial removed.

30 Fig. 3, is a view in section taken upon the line 3—3 of Fig. 2.

Fig. 4, is a detached view of one of the guides shown in Figs. 2 and 3.

Fig. 5, is a face view of one of the tumbler 35 rings.

Fig. 6, is an elevational view of the rotatable post shown in Figs. 2 and 3.

Fig. 7, is an edge view thereof.

40 Fig. 8 represents a slotted disc hereinafter referred to; and

Fig. 9, is a view of the base part detached.

For the purpose of illustrating my invention I have shown in the accompanying drawings one form thereof which is at present preferred by me, since the same has been found 45 in practice to give satisfactory and reliable results, although it is to be understood that the various instrumentalities of which my invention consists can be variously arranged 50 and organized and that my invention is not limited to the precise arrangement and organization of the instrumentalities as herein shown and described.

Referring to the drawings, the reference 55 numeral 10 designates a dished casing having

a cover plate 11 fitted thereto, which plate is provided preferably with raised graduations 12 designated for instance from 0 to 30. Within the casing is a fixed plate 12' apertured at 13, and rotatably fitted to said aperture is a disc 14, slotted at 15 and engaging which slot is the end of a flat post 16, which projects through the cover plate 11 and is provided with a knob or handle 17. Surrounding said post 16 are a series of tumbler rings 18 each provided internally with a projection 19 and externally with a notch 20. These rings are supported and guided in a circular path through fixed guides 21, radially arranged with the opposed faces thereof 60 grooved as at 22. Thus in operation as the post 16 is rotated by handle 17 the edge of said post engages with the inner projection 19 of a tumbler ring for moving same to a desired position. During this movement the butt 23 75 of a dog 24, pivoted as at 25, rides upon the peripheries of the tumbler rings the opposite end of the dog cooperates with the notched part 26 of a shackle 27 as best seen in Fig. 2. When the total number of tumbler rings 19, 80 of which three are shown in the drawings for illustrative purposes, have been properly moved so that their notches 20 are in alignment it is evident that the butt 23 of dog 24 will under the influence of gravity drop into 85 the aligned notches and thus permit the withdrawal of the notched end of the shackle from engagement with said dog. The shackle in open position, because of its cam-like end 28 abutting against the butt of the dog 24, maintains the knob, post and tumbler rings against 90 rotation since the dog is thus held firmly in the notches of said rings. It is thus apparent that with few and simple parts an efficient lock is provided, which after assembly possesses no delicate parts to become deranged and no springs to weaken and get out of order. Further, because of the simple arrangement of tumbler rings and their grooved guides 95 dislocation of said rings is practically eliminated which is most desirable in combination locks.

It will now be apparent that I have devised a novel and useful construction which embodies the features of advantage enumerated as desirable in the statement of the invention and the above description and while I have in the present instance shown and described the preferred embodiment thereof which has been found in practice to give satis- 105 110

factory and reliable results, it is to be understood that the same is susceptible of modification in various particulars without departing from the spirit or scope of the invention or sacrificing any of its advantages.

What I claim is:

1. In a lock of the character stated a casing having fixed therein radially disposed guides having opposed grooved faces, a plurality of tumbler rings rotatably fitted to said grooves, each ring having an inner projection and an outer notch, a knob, a rotatable post operative through said rings and fixed to said knob, for engaging with said projections, a shackle, and a pivotal dog one end of which is adapted to ride upon the peripheries of said rings and the opposite end of which is for engaging said shackle.
2. In a lock of the character stated a casing having fixed therein radially disposed guides having opposed grooved faces, a plurality of tumbler rings rotatably fitted to said grooves, each ring having an inner projection and an outer notch, a knob, a flat rotatable post op-

erative through said rings and fixed to said knob, for engaging with said projections, a shackle, and a pivotal dog one end of which is adapted to ride upon the peripheries of said rings and the opposite end of which is for engaging said shackle.

3. In a lock of the character stated a casing having fixed therein radially disposed guides having opposed grooved faces, a plurality of tumbler rings rotatably fitted to said grooves, each ring having an inner projection and an outer notch, a knob, a rotatable post operative through said rings and fixed to said knob, for engaging with said projections, a pivotal dog, a shackle having a pivotal cam-like end for contacting with the butt end of said dog, one end of which dog is adapted to ride upon the peripheries of said rings and the opposite end of which is for engaging said shackle.

In testimony whereof, I have hereunto signed my name.

HARRY A. BARRETT.
